UNITED STATES PATENT OFFICE.

CLAUD A. OSBORN, OF FORT WORTH, TEXAS.

FLUSHING DEVICE.

1,231,288.

Specification of Letters Patent. Patented June 26, 1917.

Application filed September 13, 1915. Serial No. 50,337.

To all whom it may concern:

Be it known that I, CLAUD A. OSBORN, a citizen of the United States, residing at Fort Worth, in the county of Tarrant and State of Texas, have invented certain new and useful Improvements in Flushing Devices, of which the following is a specification.

My invention relates to flushing devices for toilet seats and for other purposes, and the object is to provide simple flushing devices by which the flushing is done with the water under the required pressure of a system of water works and more particularly to provide devices which will permit the flow of water for a limited time and then cut off the flow of water automatically. This provision dispenses with the flushing tank and makes the flushing equipment much more economical. Other objects and advantages will be fully explained in the following description and the invention will be more particularly pointed out in the claims.

Reference is had to the accompanying drawings which form a part of this application.

Figure 1 is a side elevation of the improvements herein described. Fig. 2 is a vertical section of the same, showing a vertically moving cup in action. Fig. 3 is a horizontal section taken on the line $x-x$ of Fig. 1. Fig. 4 is a detail view of the rack and sector for operating the valve and the automatic closing devices. Fig. 5 is a bottom plan view of the valve.

Similar characters of reference are used to indicate the same parts throughout the several views.

The improved flushing device herein described comprises a valve casing 2 communicating with the pipe 1 which is connected with a water supply source. This casing 2 has a seat 3 for a valve 4 which is provided with a winged stem 5. The valve 4 is raised from its seat by an eccentric 6 which is rigid with a shaft 7. The shaft 7 is journaled at the inner end in the side of the valve casing, as shown in Fig. 2, and at the other end in a stuffing gland 8. The shaft 7 has a shoulder 9 to prevent axial movement of the shaft, the shoulder 9 engaging an inner shoulder in the stuffing gland casing. Provision is made for diverting a portion of the escaping water and discharging the same out of the side of the

casing 2. A discharge outlet 10 is formed integral with and projects within the casing and a wing 11 is also formed integral with the casing 2 to form a support for the automatic closing devices. The wing 11 is perforated at 12 for the tripping rod 13, the wing or cover 11 thus acting as a guide for the tripping rod. A rack 14 is formed on the tripping rod and a sector 15 is rigid with the shaft 7 and is meshed with the rack 14. The tripping rod is elevated by a pull cord or cable 16 which runs over an idler 17. A pull on the cord 16 will elevate the tripping rod and simultaneously raise the valve 4 by means of the eccentric 6. The idler 17 may be mounted on a bracket 18 which is mounted on the casing 2. The tripping rod 13 is connected with a cup 19 by means of a bar 20 which is attached to the cup 19 and by nuts 21. The tripping rod is thus adjustably connected to the cup 19. The cup 19 is provided with a valve 22 which is prevented from displacement by a cage 23. A trip 24 is mounted on the rod 13 and is engaged by a weighted cam 25 which is pivotally mounted in a casing 26 by a pivot bolt or rod 27. When the rod 13 is elevated, the trip 24 will ride up on the cam 25 and when the rod reaches its limit of upward travel the trip 24 will rest on the shoulder 28 which will support the rod and the cup 19 while the cup 19 is empty and until the cup is approximately full of water. The size of the cup and the weight of the cam must be adjusted by experiment until the cup catches the proper amount of water to make the cup drop. The size of the discharge outlet 10 and the cup must be gaged and timed also to make the cup fall when the flushing is complete. The casing 26 acts as a guide and protection for the cup 19 and the weighted cam 25. When the cup drops it will actuate the shaft 7 through the rack 14 and sector 15 and thus let the valve 4 close. When the cup falls the valve 22 will be opened and the water in the cup 19 will be drained through the nipple 31 into the pipe 29 which is a continuation of pipe 1. When the cup 19 is nearing the filling point, the trip 24 will bear down on the cam at 28 and slide off so that the cup 19 will fall. A float valve 32 may be loosely suspended from the cam 25 to aid in the release of the trip 25 so that the trip will be certain to release the cam at the proper time. The amount of water to be discharged through

- the pipes 1 and 29 can be further regulated by a needle valve 33. More or less water can be made to pass through the discharge 10 for the purpose of throwing the cup 19. 5 The casing 26 may be mounted on the pipe 29 by means of bands 30 and may be attached to the cover 11 by means of lugs 34. Set screws 35 may be used to tighten the bands 30 on the casing 26.
- 10 It will be seen that the flushing devices can be made to flush as long or as short a time as may be necessary or to run as much water as may be necessary. It is apparent that various changes may be made in the 15 flushing devices without departing from my invention.

What I claim, is,—

1. In combination, a valve and controlling means therefor, comprising a shaft bearing 20 at one end an eccentric adapted on rotation of the shaft to unseat the valve and on the other end the gear, a rack-bar engaging said gear, a cup secured to said rack-bar, means for intercepting a portion of the discharge 25 from the outlet side of the valve and directing it into said cup, swinging gravity tripping devices for yieldingly supporting the cup in elevated position and adapted to permit the fall of the cup when a predetermined amount of water has been received 30 therein, and means for elevating the rack-

bar whereby the valve is unseated and the cup elevated.

2. In combination, a valve and controlling means therefor, comprising a rocker shaft bearing at one end an eccentric adapted on the rocking of said shaft to unseat said valve and bearing at the other end a gear, a cup for automatically causing the seating of said valve, a reciprocating member operatively connecting said cup and said gear for actuating said gear, means for moving said reciprocating member to unseat said valve and simultaneously to elevate said cup, swinging gravity tripping devices for yieldingly supporting said cup in the elevated position but adapted to permit the fall of the cup when a predetermined amount of water accumulates in said cup, and means for intercepting a portion of the water discharged by the unseating of said valve and directing the same into said cup to cause said cup to descend and effect the reseating of said valve.

In testimony whereof, I set my hand in 55 the presence of two witnesses, this 3rd day of April, 1914.

CLAUD A. OSBORN.

Witnesses:

A. L. JACKSON,
BERT HUEY.
